(57) **CLAIM**

The ornamental design for a watch strap as shown and described.

DESCRIPTION

FIG. 1 is a top view of the invention;

FIG. 2 is a bottom view thereof;

FIG. 3 is a left side view thereof;

FIG. 4 is a right side view thereof;

FIG. 5 is a front view of a first portion thereof;

FIG. 6 is a back view of the first portion thereof;

FIG. 7 is a front view of a second portion thereof;

FIG. 8 is a back view of the second portion thereof; and,

FIG. 9 is a perspective view thereof.

The broken lines in the drawings illustrate environmental structure of the watch strap and form no part of the claimed design.
